SYSTEM FOR ASSEMBLY AND LEVELING
OF PLAYING SURFACE FOR BILLIARDS

RELATED APPLICATIONS

This is a Divisional Application of U.S. patent application Ser. No. 11/804,323 filed on May 18, 2007 now U.S. Pat. No. 7,621,818.

BACKGROUND OF THE INVENTION

1. Field of the Invention

The present invention generally relates to billiard tables and, more particularly, is concerned with a device to accelerate the assembly and leveling of a playing surface and support structure therefor so that billiards may be played on the playing surface.

2. Description of the Prior Art

Various types of pool tables have been described in the prior art. However, none of the prior art discloses the unique features of the present invention.

U.S. Pat. No. 3,913,973, dated Oct. 21, 1975, to Mentz, et al disclosed a combination pool table and couch.

U.S. Pat. No. 786,693, dated Apr. 4, 1905 to Stone disclosed a convertible sofa and table.

U.S. Pat. No. 3,988,021, dated Oct. 26, 1976, to Grover disclosed a game table.

U.S. Pat. No. 3,889,945 dated Jun. 17, 1975, to Ellis disclosed a billiard table with accessories.

U.S. Pat. No. 816,616, dated Apr. 3, 1906, to Stone disclosed a convertible sofa and table.

U.S. Pat. No. 5,882,265, dated Mar. 16, 1999, to Benton disclosed a vertically storable and self-leveling billiard table.

While these pool tables may be suitable for the purposes in which they were designed, they would not be suitable for the purposes of the present invention as hereinafter described.

SUMMARY OF THE PRESENT INVENTION

The present invention discloses a system to allow quick setup of a support structure and connected playing surface with rapid leveling of the playing surface for playing billiards. One embodiment of the invention allows the playing surface to be mounted to a support structure that can be converted to a couch. This embodiment can be placed in residential housing in rooms such as dens, family rooms, or living rooms. Another embodiment of the invention allows the playing surface when mounted to legs rigidly connected to a floor to be used on a concrete patio, a garage with a concrete floor or on a wooden deck.

An object of the present invention is to provide a device suitable for a space that is occupied by a conventional heavy billiard table in a house which can be quickly made available for other uses by quick disconnection and easy storage of the playing surface with the supporting structure being used as a couch.

Another object of the present invention is to provide a device that uses a support structure rigidly connected to the floor which enables quick setup for the game of billiards on a wooden deck or concrete floor. The support structure which consists of four legs and two supporting members can be stored on a wall along with the lightweight playing surface.

Another object of the present invention is to provide a device that can be quickly leveled using a leveling system that is manual or electrically-assisted.

Another object of the present invention is to provide a device for a set of billiard balls already racked in a triangular

2

rack and placed in a surrounding triangular storage container which speeds up the time required to attain readiness for play. To place the billiard balls onto the playing surface simply pull the rack out of the storage container and place the balls in the required position for play.

Another object of the present invention is to provide a device for a couch support structure, readily accessible cue storage being provided that negates the necessity for wall mounted cue storage. Thus the cues, billiard balls already racked, cue ball, and chalk are stored directly on-board the couch structure.

The foregoing and other objects and advantages will appear from the description to follow. In the description reference is made to the accompanying drawings, which form a part hereof, and in which is shown by way of illustration-specific embodiments in which the invention may be practiced. These embodiments will be described in sufficient detail to enable those skilled in the art to practice the invention, and it is to be understood that other embodiments may be utilized and that structural changes may be made without departing from the scope of the invention. In the accompanying drawings, like reference characters designate the same or similar parts throughout the several views. The following detailed description is, therefore, not to be taken in a limiting sense, and the scope of the present invention is best defined by the appended claims.

BRIEF DESCRIPTION OF THE DRAWINGS

In order that the invention may be more fully understood, it will now be described, by way of example, with reference to the accompanying drawings in which:

FIG. 1 is a perspective view of portions of the present invention.

FIG. 2 is a perspective view of portions of the present invention.

FIG. 3 is a perspective view of portions of the present invention.

FIG. 4 is a perspective view of portions of the present invention.

FIG. 5 is a perspective view of portions of the present invention.

FIG. 6 is a perspective view of portions of the present invention.

FIG. 7 is a perspective view of portions of the present invention.

FIG. 8 is an exploded perspective view of portions of the present invention.

FIG. 8A is a sectional view of portions of the present invention.

FIG. 8B is a sectional view of portions of the present invention.

FIG. 9A is a perspective view of portions of the present invention.

FIG. 9B is a perspective view of portions of the present invention.

FIG. 10 is a perspective view of portions of the present invention.

FIG. 11 is a perspective view of portions of the present invention.

FIG. 12 is a perspective view of portions of the present invention.

FIG. 13A is a perspective view of portions of the present invention.

FIG. 13B is a perspective view of portions of the present invention.

FIG. 14A is a perspective view of portions of the present invention.

FIG. 14B is a perspective view of portions of the present invention.

FIG. 15 is an exploded perspective view of portions of the present invention.

FIG. 16 is a perspective view of portions of the present invention.

FIG. 17 is a cross-sectional elevation view of portions of the present invention.

FIG. 18 is a cross-sectional view of a portion of the present invention along with a schematic diagram of a portion of the present invention.

LIST OF REFERENCE NUMERALS

With regard to reference numerals used, the following numbering is used throughout the drawings.

DETAILED DESCRIPTION OF THE PREFERRED EMBODIMENT

The following discussion describes in detail at least one embodiment of the present invention. This discussion should not be construed, however, as limiting the invention to those particular embodiments since practitioners skilled in the art will recognize numerous other embodiments as well. For a definition of the complete scope of the invention, the reader is directed to the appended claims. FIGS. 1-18 illustrate the present invention wherein a system for accelerated assembly and leveling of a billiard playing surface and support surface therefor is disclosed.

Billiard tables are characteristically constructed of heavy materials because the playing surface and its supporting structure must be very stable in order for the table to be 60 unaffected by bumping of the table by the player's body or by movement induced to the table by the balls hitting the rails. Ideally, there is no motion imparted to the billiard balls as the result of movement or vibration of the supporting structure. A heavy billiard table must be placed in the space where play 65 occurs and remain in the same space when the table is not being used for play. This is because of the unwieldy and difficult task of moving the heavy billiard table. Individuals

with very large homes can afford the luxury of having enough space to dedicate permanently that space required for a heavy billiard table. However, many individuals cannot afford the luxury of dedicating so much space to a billiard table. This invention is primarily intended for use by those individuals who must utilize the space required for a billiard table for other activities when the table is not being used.

With the advent of the fabrication of lightweight playing surfaces using composite materials such as foam for a core and fabric/epoxy or aluminum skins, a playing surface that is much less in weight than slate or heavy materials that imitate slate can be realized. Unlike a heavy playing surface, the composite playing surface may be lifted by two humans with relative ease and moved from its storage space to the space where the playing surface enables the game of billiards to be played. In order to achieve the required stability, the playing surface must be connected to a heavy support structure or connected to a structure that is rigidly connected to the floor.

Turning to FIGS. 1 and 2, shown therein is the interior of a room 12 having a wall 14 thereon. Also shown is couch 16 with a removable back support 18 having the removable playing surface 20 disposed on wall 14. Couch 16 has a front side, a back side and a pair of opposite ends or arms. Also shown are a pair of connecting hand bolts 22 which are mounted through apertures 24 on each end of the playing surface 20 for insertion into and attachment to the ends of the couch 16. FIG. 1 shows the playing surface removed from couch 16 with back support 18 on the couch. FIG. 2 shows the playing surface 20 being attached to the couch 16 having back support 18 removed therefrom.

Turning to FIGS. 3, 4 and 5, shown therein is shown a couch 16 having playing surface 20 thereon having a plurality of conventionally placed pockets 21 along with connecting hand bolts 22. Playing surface 20 is generally rectangular having a front side, a rear side and a pair of ends corresponding to the sides of the couch 16 and an upper and lower surface wherein billiards are played on the upper surface. Also shown are multiple casters 26 on each corner of the couch 16 along with a leveler 28 disposed at each corner of the couch. Also shown is the rear side of the couch in FIG. 5 showing a storage area for a rack and ball container 30, multiple slotted cue holders 32, a male three prong plug 34 to accept an extension cord along with a hand hole 36 needed to adjust the center support 96 having a portion thereof pass through the hand hole which center supports are located in about the middle of the front and back sides of the couch 16 and also showing end member 92 on each end having a threaded aperture 94 therein.

Turning to FIGS. 6 and 7, shown therein is the wall mounting fixtures 38 being a pair thereof which are used for receiving the playing surface 20 therein between the mounts 38 which are mounted onto the wall as previously disclosed. Each mount 38 has an upper member 37 with a downwardly disposed protrusion thereon and a lower member with an upwardly disposed protrusion thereon wherein a side of the playing surface is removably placed in the upper and lower protrusions.

Turning to FIGS. 8-10, shown therein are the stand alone legs 40 having a base 42, multiple elongated members or legs 44, a hollow axle 46, adjusting nut 48 and an upwardly disposed U-shaped lumber or 2x4 clamp 50. Metal plate 114 with aperture 115 therein spans viewing hole 113 allowing hand bolt 71 to be visually aligned with either threaded insert 70 or threaded plate 74. It can be seen that the legs 44 have a metal tubing crimped flat on one end 52 and a T-shaped connector 54 on the other end which connects the metal conduit tube to the base 42 by fitting into a slot in the tube. Adjusting nut 48 with hollow axle 56 fits in the aperture 58 of

axle 46. The 2x4 clamp 50 also has a 3/4" rod 60 thereon. Washer 111 fits around hollow axle 56 and cotter pin 112 fits into aperture 66 to prohibit vertical movement of hollow axle 56. FIG. 8A shows a cross section of 2x4 clamp 50 having a threaded rod 60 thereon with welds 62 and a horizontally disposed adjusting locking fastener 64. FIG. 8B is a cross section of adjusting nut 48 showing the end 56 and a hole 66 for receiving a cotter pin. FIG. 9A shows the stand-alone leg 40 disposed on a concrete floor 68 having a hand bolt 71 connected to a threaded lead insert 70 for attachment to the floor. FIG. 9B also shows the leg assembly 40 attached to a wooden deck 72 having a hand bolt 71 connected to a threaded plate 74 for attachment to the deck. FIG. 10 shows the legs 40 positioned as they would be on a concrete floor 68 or a wood deck 72 placed in position with 2x4 clamps 50 for receiving the 2x4 horizontal supports as herein disclosed.

Turning to FIGS. 11 and 12, shown therein are the leg members 40 having the horizontal lumber supports 76 mounted thereon to clamps 50 so that the underside of playing surface 20 can be placed on the lumber supports and using connecting bolts 22 for attaching the playing surface to the lumber supports. Lumber supports 76 may be 2x4 pieces of lumber.

Turning to FIGS. 13A and 13B, shown therein is a chalk and cue ball container 78 with lid 80 open (FIG. 13A) with attached rack and ball container 82 having the flap 84 open (FIG. 13B) for receiving a rack 86 with the balls 88 therein. The purpose of this is to allow the rack 86 to have a pre-prepared set of billiard balls 88 for placement in the container 82 so they can be deployed quickly onto a leveled playing surface. The cue ball 108 may be quickly retrieved from the cue ball container 78 with accompanying chalk 106 readily available for the tips of the cues. FIG. 13A shows the lid 80 open along with chalk 106 and cue ball 108, and FIG. 13B shows the lid closed. Container 82 is sized and shaped as rack 86 and containers 78 and 82 are attached.

Turning to FIGS. 14-16, shown therein is 14A showing the front of couch 16, back 18 (this may be a foldable hinged back support), and having a futon or mattress 90 thereon, i.e., a futon as used herein generally refers to a mattress-like member for providing a substantially flat surface for sleeping thereon, wherein the couch has an end member 92 on each end for receiving a hand bolt at aperture 94. FIG. 14B shows a center support member 96 having threaded holes 98 spaced apart therein along with a rotatable threaded rod 100, threaded nut 102, and vertically adjustable end cap 110 which member 96 is attached to the couch 16 when the couch is used to support the playing surface. The playing surface 20 is attached using the connecting hand bolts 22 with threaded portion 23 passing through aperture 24 into receiving member 92 on the couch 16 wherein the aperture 94 receives the threaded portion of the connecting hand bolt 22. The center supports 96 are shown attached to opposing sides, i.e., front and rear sides, of the couch 16 using hand bolts 104 for being connected to the front and rear sides of couch 16 about midway between the ends of the couch. The playing surface 20 with connecting hand bolts 22 is attached to the upper portion of couch 16 using the hand bolts 22 which pass through apertures 24 into the couch for attachment to the member 92 on the couch 16. Center supports 96 having vertically adjustable end caps 110 thereon are then used to steady playing surface 20 on couch 16 by having the end caps contact the bottom surface of the playing surface 20. FIG. 15 shows the hinged back support 18 folded down so as to lie flat on the futon when the couch 16 is being used to support the playing surface 20.

Turning to FIG. 17, therein is shown the cross-sectional view of leveler 28 showing knob 116, which is rotated by hand being connected to one end of threaded rod 118, which is mounted and installed in steel tube 120. Shown is schedule 40 pvc pipe 122, or like, machined to fit inside steel tube 120, along with a plastic or wood end plug 124, which fits inside the pvc pipe. Also shown is a guide 126 which prevents the pvc pipe 122 from rotating, which guide runs in a slot in the steel tube 120. Also shown is a plastic or wood plug 128 inside pipe 122 having a washer 130 thereon welded at 132 to a threaded nut 134. Also shown are mating washers 136 and cotter pins 138 which hold rod 118 inside the upper end plug/seal 140, which seal has an aperture 142 therein through which rod 118 extends. It should be understood that when a user rotates knob 116, which turns rod 118, that the inner pvc pipe 122 is moved vertically inside steel tube 120 which is attached to the end or corner of the couch 16. This thereby levels the playing surface 20 mounted on couch 16 to which leveler 28 is attached.

Turning to FIG. 18, therein is shown the leveler 28 having a dc motor 144 attached to a gear box 146 on the upper end of leveler 28. The elements of the leveler 28 include washer 136, collar 148, steel tube 120, threaded rod 118, pvc pipe 122, plastic or wood plug 124, washer 130, weld 132, guide 126, and end plug 140, all of which are substantially similar to the corresponding elements of the leveler 28 as shown in FIG. 17. Essentially the leveler 28 of FIG. 17 is equipped with a gear box 146 and dc motor 144 rotatably connected to rod 118 as shown in FIG. 18. While a dc motor and circuit are disclosed an ac motor and circuit could also be used. Also shown is an exemplary schematic circuit for an automatic direct current motor-driven leveler 28 which includes dc motor 144 which motor-driven leveler is controlled with the exemplary circuit disclosed in FIG. 18. The motor 144 is activated when the pendulum 150 (i.e., an electrical conductor), which is disposed in the level sensor 152 which is mounted on or operationally connected to playing surface 20 or couch 16, touches either plate electrode 154 or plate electrode 156. The pendulum is an electrical conductor. When the pendulum 150 touches 154 battery 158 provides a current through the coil 160 in electrical relay 162 which in turn closes contact 164 in the relay which causes battery 166 to send a current to the dc motor 144 terminal 172 which causes clockwise rotation. The dc motor 144 shaft rotation in the counter-clockwise direction is obtained when pendulum 150 contacts plate electrode 156 which causes a current to flow in the coil of relay 168 resulting in a current through battery 170 flowing to the terminal 174 of the dc motor 144. Neutral/ground terminal 176 is also shown. The dc motor 144 has no rotation when the pendulum 150 moves to an intermediate position (i.e. indicating a level condition) wherein the pendulum does not contact either electrode 154 or 156.

I claim:

1. An apparatus for assembly and leveling of a playing surface for playing billiards thereon, the playing surface having a plurality of pockets, comprising:

- a) a playing surface suitable for playing billiards thereon, said playing surface having a frame member surrounding said playing surface, and being generally rectangular and having four corners, said playing surface having top and bottom surfaces, first and second sides, and first and second ends, wherein said ends are shorter in length than said sides, wherein billiards is played on said top surface;
- b) wherein said playing surface has first and second apertures in said frame member along first and second ends of said playing surface;

- c) a leg being disposed on each said corner of said playing surface, each said leg having top and bottom ends, wherein said bottom surface of said playing surface rests on said top end of each said leg and said bottom of said leg rests on a supported surface;
- d) an upwardly disposed vertically adjustable U-shaped clamp disposed on said top of each said leg, the U-shaped clamps along said first and second sides of said playing surface having elongated openings in alignment with each other, respectively;
- e) a first piece of lumber being disposed on said pair of legs corresponding to said first side of said playing surface and a second piece of lumber being disposed on said pair of legs corresponding to said second side of said playing surface, each said piece of lumber resting in the aligned elongated openings and having a locking fastener passing through one wall of each elongated opening for releasably securing said first and second pieces of lumber in each elongated opening;
- f) said bottom surface of said playing surface resting on each of said first and second pieces of lumber with the apertures in said frame along each end of said playing surface aligned with a top edge of said first and second pieces of lumber; and,
- g) a connecting hand bolt passing through each of said first and second apertures into underlying pieces of lumber so as to removably attach said playing surface to each said leg, whereby release and reattachment of said locking fasteners and connecting bolts allow quick setup for the game of billiards.

2. The apparatus of claim 1, further comprising a rack and ball container being generally shaped to receive a rack containing pool balls therein, a chalk and cue ball container, and, wherein said rack and ball container is attached to said chalk and cue ball container.

3. An apparatus for assembly and leveling of a playing surface for playing billiards thereon, the playing surface having a plurality of pockets, comprising:

- a) a playing surface suitable for playing billiards thereon, said playing surface being generally rectangular and having four corners, said playing surface having top and bottom surfaces, first and second sides, and first and second ends, wherein said ends are shorter in length than said sides, wherein billiards is played on said top surface, and a frame surrounding said playing surface;
- b) wherein said frame along each said first and second ends of said playing surface has first and second apertures therein;
- c) a leg being disposed on each said corner of said playing surface, each said leg having top and bottom ends, wherein said bottom surface of said playing surface rests on said top end of each said leg and said bottom of said leg rests on a supported surface;
- d) an upwardly disposed vertically adjustable U-shaped clamp disposed on said top of each said leg, said U-shaped clamp for removably receiving a piece of lumber therein;
- e) a first piece of lumber being disposed on said pair of legs corresponding to said first side of said playing surface and a second piece of lumber being disposed on said pair of legs corresponding to said second side of said playing surface, wherein each said piece of lumber is disposed in said U-shaped clamp on said top of said leg, wherein each said first and second aperture is coaligned with corresponding first and second pieces of lumber;
- f) wherein said bottom surface of said playing surface rests on each of said pieces of lumber with apertures in said

9

frame along each end of said playing surface aligned with a top edge of said first and second pieces of lumber; g) wherein a connecting hand bolt passes through each said first and second apertures into underlying first and second pieces of lumber so as to removably attach said playing surface to each said leg, wherein said playing surface can be leveled by using said vertically adjustable U-shaped clamp; and h) each said leg further comprising a base disposed on a bottom end thereof and an axle disposed on a top end thereof, wherein said axle is attached to said base by a plurality of elongated members each having a first end connected to said axle and a second end connected to said base, wherein said axle has a substantially vertically disposed bore therein, said bore adapted for having a

threaded portion disposed therein, said U-shaped clamp having a downwardly disposed rod attached thereto, said rod being removably disposed in said threaded portion of said bore of said axle so that said U-shaped member can be vertically height adjusted by rotating said U-shaped clamp in said axle, said U-shaped clamp being adapted so as to removably secure each piece of lumber therein, and, said base of each said leg being adapted for being removably attached to a supporting surface.

4. The apparatus of claim 3, further comprising first and second wall mounting fixtures, wherein said fixtures are adapted to be attached to a wall, wherein said fixtures are adapted to receive said playing surface thereon.
